UNITED STATES PATENT OFFICE.

HENRY A. ROSBACK, OF CHICAGO, ILLINOIS.

CASHIER'S TICKET.

1,308,115.

Specification of Letters Patent. Patented July 1, 1919.

Application filed March 19, 1915. Serial No. 15,506.

To all whom it may concern:

Be it known that I, HENRY A. ROSBACK, a citizen of the United States, residing at Chicago, in the county of Cook and State of Illinois, have invented certain new and useful Improvements in Cashiers' Tickets, of which the following is a specification.

This invention relates to cashiers' tickets, of a kind adapted for use in restaurants, 10 lunch rooms, mercantile establishments, and the like.

The present practice in lunch rooms, for instance, is to provide each waiter with a supply of tickets having a plurality of 15 numerals printed thereon corresponding to the various prices which may be charged the customer for his meal; and after the transaction has been completed the waiter punches the ticket through or adjacent the proper 20 numeral to indicate to the customer and to the cashier the amount to be paid for the purchase. This practice makes it necessary for each waiter to carry a punch, or other instrument, for punching or cutting each 25 ticket in a manner to provide the proper significant indication.

By my invention, I overcome the necessity for the use of punching or cutting instruments, by providing a ticket having a 30 plurality of numerals printed thereon and a plurality of detachable portions located, respectively, adjacent the numerals and capable of detachment from the body of the ticket by being gripped between the fingers 35 of the waiter, or other user.

The principal object of my invention is to provide a cashier's ticket which may be manipulated to provide the desired significant indication without the use of a punch 40 or other instrument.

These and other objects of my invention will be more particularly set forth in the following specification, taken in connection with the accompanying drawing, in which—

45 Figure 1 illustrates a top plan view of one form of ticket constructed in accordance with my invention; and

Fig. 2 shows a top plan view of a portion of another ticket embodying certain modified details.

50 Referring to the drawings, my improved ticket, designated generally by the numeral 10, has printed thereon a plurality of numerals 11, corresponding to the various

prices which may be charged a customer for 55 his purchase; and these numerals are preferably arranged in rows, 12 and 13, adjacent the vertical edges, 14 and 15, respectively, of the ticket. Across the top of the ticket, above the numerals 11, is printed the legend 60 16, as follows: "Pay cashier largest amount indicated", for the direction of the customer after he receives the ticket from the waiter, or other attendant. Between the rows 12 and 13 of printed numerals, other information or advertising material may be printed 65 on the ticket, as shown at 17.

The ticket as above described is substantially the same in form and arrangement as the tickets which are now employed in connection with punching or other cutting instruments, and the principal feature of my invention relates to the provision of the ticket with a plurality of apertures 18, which are formed through the ticket between each 70 of the edges 14 and 15 and the adjacent rows 12 and 13, respectively, of the printed numerals 11. These apertures are punched or stamped through the ticket simultaneously 75 with the printing thereof, or after the completion of the printing operation, in such a manner that each of the apertures intersects the adjacent edge of the ticket and is located on a center line midway between the two adjacent numerals, as clearly shown in the 80 drawings.

This construction provides a plurality of projections or tongues 19, which are located, respectively, opposite the numerals 11, and these projections or tongues may be readily 85 detached from the body of the ticket by tearing the material from which the ticket is formed, after gripping the desired tongue or projection between the fingers of the user. It will be apparent that the detachment of 90 one of these tongues or projections, as shown at 20, will leave an enlarged aperture or notch opposite the desired numeral to indicate to the customer and cashier the amount 95 to be paid.

To guard against possible error which might arise from an incorrect alinement of the apertures 18 with the center lines between the numerals 11, I provide each of the projections 19 with a printed numeral 21, 100 which is in relatively small type and corresponds to the adjacent one of the numerals 11 opposite which it is located, so that 105

when one of the projections is detached the remaining projections will bear numerals corresponding to all of the numerals on the ticket, except the one which indicates the 5 amount to be paid.

In Fig. 2 I have shown a portion of a ticket in which the apertures 25 are punched through the ticket midway between the center lines of the adjacent numerals, but spaced 10 inwardly so as not to intersect the adjacent edge of the ticket. By this construction intervening portions 26 are formed which are readily detachable from the body of the ticket, while at the same time the edge of the 15 ticket is left smooth, thereby preventing the possibility of accidental detachment of any of the detachable portions opposite the numerals. It may be preferable in some instances to locate the apertures outwardly toward the edge of the ticket to a greater extent than above described, as shown at 27 in Fig. 2. This method permits the formation of the apertures 27 in two adjacent tickets at the same time by the use of a very 20 simple and inexpensive form of punch.

Although I have referred to my improved ticket, in the appended claims, as being formed of cardboard or the like, it will be understood that it may be formed of any 30 suitable material which would be the substantial equivalent of cardboard and which would permit the operation of the ticket in practice as herein explained.

It will be understood that the particular 35 form and arrangement of the elements of the ticket and the particular method of use described may be altered without departing from the spirit of my invention as defined by the appended claims.

40 I claim:—

1. A cashier's ticket formed of cardboard and having a row of numerals printed thereon, and a plurality of apertures therethrough, adjacent to and outwardly from 45 said numerals with respect to the adjacent edge of the ticket, one of said apertures being located on a line substantially midway between each pair of successive numerals, whereby a detachable portion is formed opposite each numeral.

2. A cashier's ticket formed of cardboard or the like and having a series of numerals printed thereon adjacent to and spaced inwardly from one edge of said ticket, and a 55 plurality of detachable portions formed integrally with the body of said ticket and adapted to be detached therefrom by a tearing motion of the fingers of the user, said ticket being imperforate between the body 60 thereof and said detachable portions, one of said detachable portions being located opposite each of said numerals.

3. A cashier's ticket formed of cardboard or the like and having a series of numerals 65 printed thereon adjacent to and spaced in-

wardly from one edge of said ticket, and a plurality of detachable portions formed integrally with the body of said ticket and adapted to be detached therefrom by a tearing motion of the fingers of the user, said 70 ticket being imperforate between the body thereof and said detachable portions, one of said detachable portions being located opposite each of said numerals, each of said detachable portions having printed thereon a numeral corresponding to the first-mentioned numeral opposite thereto. 75

4. A ticket formed of cardboard or the like and having a plurality of numerals printed thereon and arranged in a row adjacent one edge of the ticket and spaced inwardly therefrom, said ticket being punched between said edge and said row of numerals to form a row of apertures which are staggered with respect to the numerals of said 80 row, whereby detachable portions are formed, each of which is attached to the body of the ticket at three points, one of said detachable portions being located opposite each of said numerals. 90

5. A ticket formed of cardboard or the like and having a series of numerals printed thereon adjacent to and spaced inwardly from an edge of said ticket, said ticket having a plurality of apertures formed therein 95 on said edge, one of said apertures being located on a line passing between each pair of successive numerals whereby a detachable portion is formed between each of said numerals and said edge of said ticket, each of said detachable portions being integral with 100 said ticket and having printed thereon a numeral corresponding to that one of the first named numerals which is located opposite thereto. 105

6. A ticket formed of material capable of being torn and having a series of numerals printed thereon adjacent to and spaced inwardly from an edge of said ticket, said ticket having a plurality of apertures formed 110 therein on said edge, one of said apertures being located on a line passing between each pair of successive numerals whereby a detachable portion is formed between each of said numerals and said edge of said ticket, 115 each of said detachable portions being integral with said ticket and having printed thereon a numeral corresponding to that one of the first named numerals which is located opposite thereto, said ticket also having printed thereon instructions to the user to pay the cashier the highest amount indicated by the detachment of said detachable portions. 120

7. A cashier's ticket formed of cardboard and having a plurality of numerals printed thereon and arranged in a row adjacent one edge of the ticket and spaced inwardly therefrom, said ticket having apertures therethrough between said edge and the 130

row of numerals whereby detachable portions are formed between said apertures, said detachable portions being united to each other at their outer extremities along said edge of said ticket, one of said detachable portions being located opposite each of said numerals.

In testimony whereof I have subscribed my name.

HENRY A. ROSBACK.
